UNITED STATES PATENT OFFICE.

CLARK S. COMSTOCK, SR., OF EAST ORANGE, NEW JERSEY.

GARMENT-SLIDE.

1,277,548.

Specification of Letters Patent. Patented Sept. 3, 1918.

Application filed April 11, 1918. Serial No. 227,920.

To all whom it may concern:

Be it known that I, CLARK S. COMSTOCK, Sr., a citizen of the United States of America, residing in East Orange, in the county 5 of Essex and State of New Jersey, have invented certain new and useful Improvements in Garment-Slides, of which the following is a specification.

This invention relates to garment slides 10 and aims to provide certain improvements therein.

The common form of garment slide comprises a metal frame having a top, bottom and sides, the sides being connected by a 15 center bar which extends the full length of the frame. In the application of a strap to this form of slide it is necessary to thread the strap through the spaces between the center bar and the top and bottom. In the 20 manufacture of suspenders or overall straps this occasions a very considerable amount of time in the aggregate. In addition to this it is customary to form a loop in the end of the strap where it passes over the 25 center bar and to sew the parts together so that the end of the strap cannot escape from the slide. This also is inconvenient and takes considerable time. It has been heretofore proposed to construct such a slide 30 with the center bar in two parts which extend from opposite sides of the frame, the two parts being of equal length and extending approximately to the middle of the frame. By this means it has been proposed 35 to work the strap onto the center bar by passing its edge up through the separating space between the two parts. In practice this has been quite difficult since after the strap has been engaged with one part of the 40 bar, the unengaged half must be compressed sufficiently to enable its further side to pass upwardly through the space between the two parts in order that it may engage the remaining part. This has required almost as 45 much trouble as is occasioned in the use of slides having a continuous center bar. Such slides are usually made of wire and in the type last described the two ends of the wire have been united by a ferrule, the use of 50 which has required additional metal and another operation in manufacture.

According to the present invention I provide a slide in which the strap can be very easily engaged with the center bar and without 55 the necessity of crushing or forcing the strap entirely to one side of the frame in

order to engage it therewith. To this end I provide a slide having a center bar which is connected to one side of the frame and which extends inwardly toward the other side to 60 a point which is well past the middle of the frame. The inserting opening is hence displaced to a point which lies close to the other side and practically no compression or crumpling of the strap is necessary in 65 order to engage it with the slide. The invention in its preferred form also obviates the use of ferrules and provides a construction formed of a single piece of wire which may be very cheaply and easily manufactured. The invention also includes means whereby the slide when adjusted to a certain position is held with great rigidity therein so that there is no chance of slipping either when the strap is taut or loose. 70 Other features of improvement will be hereinafter more fully described. 75

In the drawings which illustrate several embodiments of the invention,

Figure 1 is a front or face view of a strap 80 showing the slide in position therein;

Fig. 2 is a central section of Fig. 1 looking to the left;

Fig. 3 is a view showing the strap and slide at the commencement of the applica- 85 tion of the former to the latter;

Fig. 4 is a view of a modified form.

Referring to the drawings, let A indicate any suitable strap or webbing, that shown being a suspender strap, and B a button loop 90 adapted to engage the suspender buttons of the trousers. Fig. 2 shows the usual mode of applying the strap to the slide; in this figure it will be noted that the extreme end of the strap is passed around the center bar 95 of the slide and is preferably sewn together at C to form a loop D. The strap is then passed downwardly around the upper bar of the button loop and thence upwardly and passed through the slide as shown. 100

In the drawings I have illustrated the preferred form of slide, which comprises a construction formed of a single piece of wire having an upper or top bar E, a lower or bottom bar F, and sides G and H, respectively. I is the center bar which, as shown, comprises two thicknesses of wire, the bar being formed by bending in an elongated loop of tongue from one of the sides, as G.

It is characteristic of the present invention 115 that the center bar I extends inwardly toward the side H to an extent which is well

past the middle of the frame. This leaves an insertion opening J through which the strap is passed in order to engage it with the bar. It will be seen by reference to Fig. 5 3 that the act of inserting is extremely easy and simple and that no particular crumpling or forcing together of the strap is necessary. This is in sharp distinction to the two-part construction hereinbefore referred to, 10 wherein such a degree of compression of the strap was necessary that the operation of assembling was difficult and inconvenient.

The present invention permits the preformation of the loop D before assembling, 15 which is a valuable feature since it is much easier to form this loop in the strap before it is applied to the slide than after the application is made. But, whether the loop is formed in advance or not, the application is 20 easy and rapid. Not only is such easy application of the loop possible with the present construction, but it is entirely feasible to insert the loop and strap together into the slide without any threading operation. To 25 accomplish this the strap is arranged substantially as in Fig. 2 and both the body of the strap and the loop inserted at one operation. This greatly economizes the time in assembling.

30 It is found in practice that the center bar I is amply strong to resist any strain which can ordinarily be put upon the suspender so that there is no danger of breakage.

It is preferred to bend the side H inwardly 35 to a slight extent, as shown in the drawing, thus not only conforming this side generally in contour to the opposite side G and thus giving the slide a symmetrical shape, but also for the purpose of providing a supporting portion K which engages the extreme 40 edge of the strap and acts to some extent to support the latter. Such portion K may be extended farther in toward the buckle if desired, but it should not be so elongated as to 45 destroy the characteristic feature of an insertion opening located well toward one side of the buckle whereby the application of the strap is facilitated.

While the slide as thus described provides 50 a very secure hold upon the strap, it is possible to increase this grip so that it is capable of bearing most unusual strains. This is accomplished by the present invention without danger of injury to the strap. For 55 this purpose I provide a pair of prongs P, Q, which—when the frame is made of a single piece of wire as shown—are easily constructed by utilizing the two ends of the wire. These prongs are of novel proportion 60 and arrangement. It will be seen that the portions R and S of the upper bar E are mainly relied upon to hold the strap in position, and if these portions were continued toward each other in a straight line and then 65 bent inwardly to form the prongs, the

prongs would extend too far in toward the middle of the frame, thus requiring a widening of the frame and consequently an increased cost. This would be true, owing to the fact that metal of practically full size 70 must be left at the bend and enough metal left to form the prongs to permit the tapering thereof to a point.

By the present invention the ends of the wire are bent upwardly to form loops T and 75 then inwardly to form the prongs. This permits the formation of prongs of proper proportions without increase of the general width of the slide and without substantial increase of metal.

80 Another valuable feature of this construction is that the prongs may be made to project into the recess occupied by the strap only to such extent as to permit of proper action upon the strap without undue penetration thereof. It will be seen from Fig. 1 of the drawing that the prongs project only a short distance inwardly of the inner limiting face of the portions R, S. The result of 85 this construction is that the portions R, S take most of the strain and the prongs act to insure against movement of the strap without undue penetration and without injury to the latter. If the upper side of the buckle were straight and the prongs bent 90 inwardly therefrom, they would be apt to penetrate deeply into the fabric and so mar or destroy the latter. Preferably the prongs in the present instance are bent in the plane 95 of the buckle, as shown in Fig. 2, so that 100 they lie substantially flat along the fabric and penetrate only at the bend. By this means injury to the strap or clothing is prevented.

105 The provision of the prongs not only makes absolutely secure the adjustments while a strain is on the strap, but also secures a fixity of adjustment when the strain is released or slackened. Heretofore there has been a tendency for the slide to move 110 when the strain on the strap has been insufficient to bind it tightly against the portions of the slide.

115 In Fig. 4 the prongs P and Q are omitted and the ends of the wire curved back so as to present smooth edges to the strap.

120 It will be seen that the invention provides an important improvement in slides of this type and that in the present construction the use of ferrules or other connecting means between the two ends of the wire are avoided. The slide is hence very cheaply constructed by the use of a single piece of material.

125 While I have shown and described several forms of the invention, it will be understood that I do not wish to be limited thereto, since various changes may be made therein without departing from the spirit of the invention.

What I claim is:

1. A garment slide comprising a frame and a center bar, said bar extending from one side of the frame inwardly toward the other side thereof to a point well past the middle of the frame, and terminating at a sufficient distance from the side of the frame to permit insertion of a strap between the end of the bar and the adjacent side of the frame without bending said bar away from the frame, said adjacent side of the frame having an inwardly-directed supporting portion extending toward the bar for engagement with one edge of the strap.
2. A garment slide comprising a frame, a center bar extending lengthwise of the frame to a point beyond the middle and spaced from the end sufficiently to permit the insertion of a strap without bending the bar away from the frame, said frame having its

extreme ends extending initially outwardly and thence inwardly relatively to said center bar to form prongs directed toward the interior of the frame.

3. A garment slide comprising a frame and having a lower bar, side bars and a top bar, the wire projecting from one of the side bars inwardly to form a center bar which extends well past the middle of the slide, and the wire of the other side bar extending inwardly to form a support for the web, and the two ends of the wire extending toward each other to form a top bar in substantially parallel relation with the lower bar, and then outwardly and then inwardly to form prongs for engaging the strap.

In witness whereof I have hereunto signed my name.

CLARK S. COMSTOCK, Sr.
